TRAY SET

David Heller, Brooklyn, N. Y., assignor to Hi-Lo Corporation, New York, N. Y., a corporation of New York

Application March 21, 1941, Serial No. 384,456

8 Claims. (Cl. 211—133)

This invention relates generally to tray sets. More particularly my invention is directed to a novel construction for extensible tray sets.

One of the objects of my invention is to provide a novel tray set of the class described, having a plurality of superimposed trays, in which the said trays may be relatively moved with respect to each from a nested position to an extended position so that the same may be used either as a single tray, or as a tray set consisting of any desired number of trays spaced one above the other.

Another object of my invention is to provide a novel construction for a tray set of the class described, which shall comprise relatively few and simple parts, which shall be relatively inexpensive to manufacture, which shall be easy to assemble and which at the same time shall operate with a high degree of efficiency, representing a general improvement in the art.

Other objects of my invention will become apparent in the following detailed description hereof.

In the accompanying drawing

Fig. 1 is a vertical sectional view, partly in elevation, of a tray set constructed in accordance with my invention and showing the same in its fully extended position;

Fig. 2 is an elevational view thereof, partly in section, but of smaller size and illustrating the same in fully collapsed position;

Fig. 3 is a fragmentary bottom plan view of the tray set shown in Fig. 1;

Fig. 4 is an enlarged cross-sectional view taken substantially on the line 4—4 of Fig. 1;

Fig. 5 is a view similar to Fig. 1, but illustrating a modified form of my invention; and

Fig. 6 is an elevational view of the Fig. 2 form of my invention, but of reduced size and illustrating the same as mounted on a support.

Referring now in detail to the drawing, I have shown a tray set of the type generally employed in homes and used for cakes, cookies, candies and the like, and which in the present embodiment comprises three trays 10, 11 and 12 spaced one above the other a predetermined distance. In accordance with my invention, I have provided the following construction whereby the said trays 10, 11 and 12 may be collapsed from the extended position shown in Fig. 1 to the position shown in Fig. 2 where it may be utilized as a single tray or in which condition it may be stored. In the latter event it is noted that the storage space required will be a great deal less than that required for the type of tray set heretofore manufactured in which the trays are always in permanently extended position and cannot be collapsed.

Attached to the lowermost tray 10 is a tubular member 15 of a predetermined diameter, the said

tube 15 being attached to the tray 10 in any suitable manner. One method of attachment is that shown in Fig. 1 of the drawing in which a portion 15a of the tube 15 adjacent a lower edge thereof passes through a central opening 16 in the tray 10 after which the material is bent over and crimped against the said tray. The tube 15 will thus be permanently and rigidly attached to the tray 10 for movement therewith. Attached to the intermediate tray 11 is tubular member 17, similar in construction to the tube 15 and similarly rigidly attached to the tray 11 for movement therewith as the tube 15 is attached to the tray 10. Similarly the uppermost tray 12 has rigidly and permanently attached thereto for movement therewith a tubular member 18, similar to the tubular members 15 and 17, but of larger diameter. The diameter of the tube 17 is such that it will be slidably received over the tube 15 and the diameter of the tube 18 is such that the same will be slidably received over the tube 17. It is thus seen from the above described construction that when the tray device is in its collapsed position with the uppermost tube 18 slidably moved so as to cause the tray 12 to lie above tray 10 as shown in Fig. 1, the tube 15 will be nested within the tube 17 and the tubes 15 and 17 will in turn be nested within the tube 18 so that only the tube 18 will be visible when the tray set is in collapsed position.

For interconnecting the trays 10, 11 and 12 so that they may be moved from collapsed to extended position or vice versa, I have provided the following means:

Attached adjacent the top end of the tube 18 is a rigid washer member 19. Permanently and rigidly attached to the said washer 19, at the center thereof and depending therefrom, is a tubular member 20 of relatively small diameter, the said tube 20 being attached to the washer 19 by any suitable means, such as, for example, a screw 21 passing through the top wall of the tubular member 20 and through the washer 19. The said screw 21 may also be utilized for attaching to the tube 18 and to the washer 19 a finger gripping member 22 to facilitate the extending and collapsing movements of the tray set. It is thus seen that the tube 20 will move with the tube 18 and with the tray 12. Attached to the tube 17 for movement therewith in the following manner, is a tubular member 23. The said tube 17 is provided at the top with a bent over wall portion 24 which terminates in an inner rounded edge 24a. The said rounded edge 24a is adapted to be received in a corresponding circumferential recessed groove 25, adjacent to the upper end of the tube 23. The tube 23 is in turn slidably interconnected to the tubular member 15 by an intermediate tubular member 30, said tube 30 being slightly larger in diameter than

the tube 23 and slightly smaller in diameter than the tube 15. It is thus seen that when the uppermost tubular member 18 is brought down to the collapsed position shown in Fig. 2, the tubes 20, 26, 23 and 30 will all be nested within the tubular member 15.

To retain the trays 10, 11 and 12 in any desired extended position, I provide a series of resilient leaf springs 31, 32, 33 and 34. The leaf springs 34 are circumferentially spaced from each other and interposed between the tube 15 and the tube 30 as clearly shown in Figure 4 of the drawing. The leaf springs 33, 32 and 31 are similarly circumferentially spaced and interposed between the tubes 30 and 23, 23 and 26, and 26 and 20 respectively. The said series of leaf springs 31 to 34 are arched or bowed so as to resiliently and frictionally hold the nestable tubular members 20, 26, 23, 30 and 15 in any extended or collapsed position. In order to change the relative positions between the trays 10, 11 and 12, it is necessary to exert a slight force to overcome the frictional action of the leaf springs 31 to 34.

In order to retain the leaf springs 31 in their proper position between the tubes 20 and 26 at all times whether the tray set is extended or collapsed, I provide a pair of circumferential beads 35 in the wall of the tube 20 and disposed adjacent to and on opposite sides of the leaf springs 31. Similarly the leaf springs 32 are retained in position by means of a pair of circumferential beads 36 in the tube 26. The leaf springs 33 are retained in position by a pair of circumferential beads 37 in the tube 23, and the leaf springs 34 are retained in position by a pair of circumferential beads 38 in the tube 30.

Each of the trays 10, 11 and 12 may be provided with centrally disposed upwardly dished portions 10a, 11a and 12a, respectively. It is noted that the dished portion 11a of the tray 11 is slightly larger than the dished portion 10a of the tray 10, and the dished portion 12a of the tray 12 is slightly larger than the dished portion 11a of the tray 11. In view of the above described dished construction of the trays, it is seen that when the tray set is in completely collapsed position as in Figure 2, the said trays 10, 11 and 12 will be in nested position so that the three trays will appear as a single tray. To that end, also, the diameter of the trays 10, 11 and 12 would be made progressively smaller with the tray 10 having the largest diameter.

To facilitate the movement of the tray set to extended or collapsed position, I have provided at the base of the set a bail member 40 having the ends 40a thereof, freely passing through the opening 16 in the dished portion 10a of the tray 10 and bent over and resiliently held in position within the circumferential bead 41 of the tube 15. The bail member 40 may be pivotally moved to lie flat within the dished portion 10a, as shown in Figure 3 when not in use. When it is desired to either extend or collapse the tray set, the bail member 40 is pivotally moved to the position shown in Figure 1 where the finger of one hand may be inserted in the loop of the bail member 40 and with the other hand gripping the finger-piece 22, at the top, the device may be actuated.

In Figure 5 of the drawing, I have shown a modified form of my invention, in which the trays 10', 11' and 12' (similar to the trays 10, 11 and 12) may be employed and in which the said trays are permanently attached to tubular members 50, 51 and 52 in the same manner that the tubes 15, 17 and 18 are attached to the trays

10, 11 and 12. In this form of my invention, a plurality of nested tubular members are employed to permit the alteration of the relative distances between the trays 10', 11' and 12'. However, such nested tubes are differently arranged from the construction shown in Figure 1.

In the Figure 5 form of my invention, the connection between the trays 10' and 11' are made by a tube 53 of relatively small diameter, which 10 is permanently attached to tube 51 by having a top wall portion 51a thereof permanently attached to the top wall 53a of the tube 53 by means of a rivet 54. An intermediate tube 55 larger in diameter than the tube 53 and smaller 15 in diameter than the tube 50, slidably interconnects the tube 53 with the tube 50. The tube 51 is interconnected with the tube 52 by means of an intermediate tube 56, larger in diameter than the tube 51 and smaller in diameter than 20 the tube 52. Interposed between the tubes 56 and 52 is a tube 57 slightly smaller in diameter than the tube 52 and disposed adjacent the inner wall thereof. The said tube 57, as well as the tube 52 are rigidly attached to the fingerpiece 25 22 by means of a washer 58 and the screw 59, in a manner similar to the attachment of the tube 18 to the fingerpiece 22. A series of circumferentially spaced leaf springs 60, 61, 62 and 63, are employed between adjacent pairs of 30 nested tubes to frictionally maintain the said tubes in any desired extended or collapsed position. The series of leaf springs 60 to 63 perform the same function as the series of leaf springs 31 to 34 and are maintained against displacement 35 and withdrawal from the tubes, by circumferential beads similar to the pairs of beads 35 to 38.

In the two forms of my invention, I have illustrated the tray set as being so constructed that the lowermost tray serves as a base or support 40 for the tray set either in its extended or collapsed position. In Fig. 6, however, I have shown a modified form of my invention in which the tray set is constructed as in the Fig. 1 to 4 or Fig. 5 forms of my invention, but instead of using the lowermost tray as the base of the device, I provide an additional support comprising a base member 70 with an upstanding stem of 71, the said stem being attached to the lowermost tray.

In Fig. 6 the tray set is shown in collapsed 50 position, and in this form the same may be utilized as an ornamental piece, even when not in actual use, and may be of such height as to stand from the floor. When it is desired, however, this tray device may be extended to the 55 positions shown in either Fig. 1 or Fig. 5.

While in the drawing I have illustrated my invention as constructed with three trays, it is understood that any other number of trays may be satisfactorily employed and that my invention extends to such use; also it is noted that any suitable style of tray may be utilized, the same being made from any suitable kind of material.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other means. Also while it is designed to use the various features and elements in the combination and relations described, some of these may be altered and others omitted without interfering with the more general results outlined, and the invention extends to such use.

Having described my invention, what I claim and desire to secure by Letters Patent is:

1. In an extensible device of the class described, a lowermost tray, an uppermost tray, a first tubular member fastened to said lowermost tray for movement therewith, a second tubular member fastened to said uppermost tray for movement therewith and extensible means interconnecting said first and second tubular members, whereby the relative distance between said trays may be altered, said extensible means comprising a plurality of slidably nestable members, means for limiting the movement of said uppermost tray in a direction away from said lowermost tray, and means for maintaining said uppermost tray in said last named limited position as well as in any intermediate position.
  2. In a device of the class described, a lowermost tray, an uppermost tray, a first tubular member fastened to said lowermost tray for movement therewith, a second tubular member fastened to said uppermost tray for movement therewith and extensible means interconnecting said first and second tubular members, said extensible means comprising a plurality of slidably nestable members adapted, when the device is in fully collapsed position, to be nested within said first tubular member, said first tubular member being in turn nestably received within said second tubular member to cause said uppermost tray to overlie said lowermost tray, means for limiting the movement of said uppermost tray in a direction away from said lowermost tray, and means for maintaining said uppermost tray in said last named limited position as well as in any intermediate position.
  3. In an extensible device of the class described, a lowermost tray, an uppermost tray, an intermediate tray, a first tubular member fastened to said lowermost tray for movement therewith, a second tubular member fastened to said uppermost tray for movement therewith and a third tubular member fastened to said intermediate tray for movement therewith, said first, second and third tubular members being relatively slidably movable to a position where said first tubular member is nested within said third tubular member and said first and third tubular members are nested within said second tubular member to cause said uppermost tray to be nested within said intermediate tray and said uppermost and intermediate trays to be nested within said lowermost tray, means for limiting the movement of said uppermost and intermediate trays in a direction away from said lowermost tray and means for maintaining said uppermost and intermediate trays in said last named limited position as well as in any desired intermediate position.
  4. In a device of the class described, a lowermost tray, an uppermost tray, an intermediate tray, a first tubular member fastened to said lowermost tray for movement therewith, a second tubular member fastened to said uppermost tray for movement therewith, a third tubular member fastened to said intermediate tray for movement therewith and extensible means interconnecting said second and third tubular members with each other and with said first tubular member, means for limiting the movement of said uppermost and intermediate trays in a direction away from said lowermost tray and means for maintaining said uppermost and intermediate trays in said last named limited position as well as in any desired intermediate position.
  5. In a device of the class described, a lower-
- 75
- most tray, an uppermost tray, a first tubular member fastened to said lowermost tray for movement therewith, a second tubular member fastened to said uppermost tray for movement therewith, extensible means interconnecting said first and second tubular members, said extensible means comprising a plurality of slidably nestable members, means for limiting the movement of said uppermost tray in a direction away from said lowermost tray and means for maintaining said device in any desired extended position, said last named means comprising a resilient member frictionally interposed between adjacent pairs of said slidably nestable members.
- 15 6. In a device of the class described, a lowermost tray, an uppermost tray, a first tubular member fastened to said lowermost tray for movement therewith, a second tubular member fastened to said uppermost tray for movement therewith, extensible means interconnecting said first and second tubular members, said extensible means comprising a plurality of slidably nestable members, means for limiting the movement of said uppermost tray in a direction away from said lowermost tray and means for maintaining said device in any desired extended position, said last named means comprising a resilient member frictionally interposed between adjacent pairs of said slidably nestable members.
- 20 25 30 35 40 45 50
7. In a device of the class described, a lowermost tray, an uppermost tray, a first tubular member fastened to said lowermost tray for movement therewith, a second tubular member fastened to said uppermost tray for movement therewith, extensible means interconnecting said first and second tubular members, said extensible means comprising a plurality of slidably nestable members, means for limiting the movement of said uppermost tray in a direction away from said lowermost tray, means for maintaining said device in any desired extended position, said last named means comprising a resilient member frictionally interposed between adjacent pairs of said slidably nestable members and means for causing said resilient member to travel with one of said pair of adjacently disposed nestable members.
- 40 45 50
8. In a device of the class described, a lowermost tray, an uppermost tray, a first tubular member fastened to said lowermost tray for movement therewith, a second tubular member fastened to said uppermost tray for movement therewith, extensible means interconnecting said first and second tubular members, said extensible means comprising a plurality of slidably nestable members, means for limiting the movement of said uppermost tray in a direction away from said lowermost tray, means for maintaining said device in any desired extended position, said last named means comprising a resilient member frictionally interposed between adjacent pairs of said slidably nestable members and means for causing said resilient member to travel with one member of said pair of adjacently disposed nestable members, said last named means comprising a pair of circumferential beads in said last named nestable member for holding said resilient member captive therebetween.
